UNITED STATES PATENT OFFICE

99,637

DESIGN FOR A DECORATIVE LIGHTING UNIT

Abraham Abramson, New York, N. Y., assignor,
by mesne assignments, to G. B. G. Corporation,
Newark, N. J., a corporation of New Jersey

Application May 13, 1935, Serial No. 56,807

Term of patent 7 years

To all whom it may concern:

Be it known that I, Abraham Abramson, a citizen of the United States, residing at New York city, in the county of Bronx and State of New York, have invented a new, original, and ornamental Design for a Decorative Lighting Unit, of which the following is a specification, reference being had to the accompanying drawing, forming part thereof.

Figure 1 is a top view, Figure 2 is a side view, and Figure 3 is a bottom view of a decorative lighting unit showing my new design.

I claim:

The ornamental design for a decorative lighting unit, as shown.

ABRAHAM ABRAMSON.
